UNITED STATES PATENT OFFICE.

AUGUSTE GOSSÉ, OF PARIS, FRANCE, ASSIGNOR TO THE SOCIÉTÉ FRANÇAISE DE CONSTRUCTIONS MÉCANIQUES (ANCIENS ÉTABLISSEMENTS CAIL), OF PARIS, FRANCE.

BOILER.

Application filed March 27, 1923, Serial No. 628,137, and in France April 4, 1922.

- My invention relates to improvements in steam generators which comprise one or more steam and water drums and one or more sets of vaporizing tubes, separate from the steam and water drums.
- It is a recognized fact that a great mass of water is required in the boilers intended to ensure an irregular service of vaporization, in order to avoid the rapid and excessive falls of pressure at the moments of abnormal demands for steam. However such great mass of water is a hindrance to rapidly raising the pressure in case this has fallen for any reason.
- One object of my invention is to provide means whereby the mass of water in the boiler drum or drums may be placed at will in the circuit of the water circulating through the vaporizing tubes or removed from said circuit. The advantages of boilers containing a great volume of water are thus obtained when placing the mass of water in the circuit and all the drawbacks of said boilers are avoided by removing said mass of water from the circuit when desired.
- In the appended drawings and by way of example:
- Fig. 1, is a diagrammatic view of a boiler in which the various elements have been spread out upon a common plane so as to better illustrate the disposition which characterizes the invention; Figs. 2 and 3 are views similar to Fig. 1 and showing slight modifications.
- Fig. 4 is a diagrammatic elevational view showing how my invention may be applied to a standard type of boiler.
- Fig. 5 is the end view thereof.
- As shown in Fig. 1, the mass of water *a* is contained in a steam and water drum *b* connected at its upper part by the pipe or pipes *e* with the upper end of a set of vaporizing tubes *d* which first receives the action of the gases of the furnace. A downwardly extending pipe *h* is connected at *p* with the upper part of the drum *b* on a level below the header *e* and is connected to another pipe *k* by means of a box *m* containing a flap valve *n*, said box being also connected with the lower part of the drum *b* by means of the pipe *o*. The valve *n* which may be controlled from the outside is adapted to close either the pipe *h* or the pipe *o* or to take any intermediate position between these two end positions. In this latter case, pipe *h* constitutes a by-pass connection between the water outlets *p* and *o* of drum *b*.
- The pipe *k* is connected at the bottom with the lower part of the set of vaporizing tubes by the mud collector *r* and pipe *q*.
- The water feed to the boiler takes place through a pipe *t* connected to the lower part of drum *b*. A steam superheater is shown diagrammatically at *v*.
- The embodiment shown in Fig. 2 is similar to that of Fig. 1 with the exception that the boiler comprises a steam and water drum *b*, and a water drum *c*, placed one above the other and in direct communication with each other. *u* is a water heater.
- In the construction shown in Fig. 3 a collector *e'* is interposed between the set of vaporizing tubes *d* and the pipe *e* while another collector *s* affords communication between the pipe *k* and the set of tubes *d*.
- In Fig. 1, the flap valve *n* is shown in its position for closing the pipe or by-pass connection *h* and in Figs. 2 and 3 it is shown in its position for closing the pipe *o*.
- Figs. 4 and 5 are merely given by way of illustration to show the positions the various parts of my invention occupy when applied to a boiler of standard construction. Since similar parts have been given similar reference characters, these figures are thought to be understood without further explanation.
- The operation of my device is as follows. If the valve *n* is in the position shown in Fig. 1, the pipe *h* is closed and the pipe or coupling *o* is opened. The water in the tubes *d* being heated by the hot gases from the furnace rises and flows through the header *e* and into the steam space of drum *b* where it is partially drawn off in the form of steam. Since pipe *h* is now closed the water entering drum *b* which is not converted into steam, upon cooling slightly circulates down through the mass of water *a*, through outlet *o*, pipe *k*, mud drum *r*, header *q* and finally back into tubes *d* where it is re-heated.
- The mass of water *a* is thus included in the water circuit.
- If the flap valve *n* is in a position to close the pipe *o* and open the pipe *h*, as shown in Figs. 2 and 3, then the circulating water no longer passes down through the entire mass of water *a* but only through a small portion of the hottest portion thereof. The water upon leaving header *e* now circulates

through the upper portion of the mass of water *a*, out through the opening *p*, the by-pass constituted by pipe *h*, pipe *k*, drum *r*, header *q* and back into tubes *d*. The 5 boiler now has but a small quantity of its water in circulating relation with its water tubes which gives it a flash characteristic and permits the boiler to supply a sudden increase in demand of steam very rapidly.

10 If the valve *n* is placed in an intermediate position then the circulation takes place through pipe *h* as just described but at the same time part of the water circulates through the mass of water *a* and raises its 15 temperature.

Thus when the demand for steam on the boiler is normal, the valve is turned to close the opening *h* and circulate the water of tubes *d* through the whole mass of water 20 *a* contained in drum *b*, the boiler thus functioning as an ordinary water-tube boiler in a manner well known in the art. When for any reason the pressure has fallen and must be rapidly raised, then the valve is turned 25 to open pipe *h* and close the outlet *o* thus cutting the large mass of water out of the circuit of the water circulating through pipes *d*. In this manner, the low temperature of this mass of water does not oppose 30 the rapid rise in pressure.

It should be noted that if the fall of pressure is chiefly due to an abnormal and much continued demand for steam, feed water should be supplied to the boiler; this additional feed, which usually increases the difficulty in raising the pressure, has no detrimental action in my improved boiler inasmuch as the feed takes place through *t* at the lower part of the drum *b* or *c*, while the 35 upper part of the mass of water *a*, that is to say the warmest part of this mass, is alone progressively inserted into the water circuit in order to replace the water which is vaporized in the set of vaporizing tubes *d*.

40 When the steam pressure has been raised to its normal value, the valve *n* is gradually turned to open the outlet *o* so that the mass of water *a* will be gradually placed in the circuit and reach progressively the general 45 temperature without causing a fall in pressure.

Obviously my invention is applicable to all types of boilers comprising a mass of water contained in one or more drums combined in any desired manner and one or more sets of vaporizing tubes. The mass of water 55 may be heated or not by the gases and the drums may be constructed with or without smoke tubes. The set of vaporizing tubes 60 may of course be of any desired construction and arrangement.

Having now described my invention what I claim as new and desire to secure by Letters Patent is:

65 1. A water-tube boiler comprising in com-

bination, a combustion chamber, a source of heat within said chamber, a plurality of water-tubes subjected to the hot combustion gases of said source of heat, a steam and water drum having a steam space therein, 70 a steam outlet for said steam space provided at the upper extremity of said drum, a water outlet near the upper end of said drum, a second water outlet near the lower end of said drum, a by-pass conduit connecting said 75 outlets, means connecting the lower end of said by-pass and said second outlet to the lower ends of said water tubes, distinct return means for connecting the upper end of said water-tubes to the steam space in said 80 drum and means for governing simultaneously the flow from said outlets to said connecting means.

2. A water tube steam generator comprising in combination a combustion chamber, 85 a source of heat within said chamber, a set of water tubes subjected to the hot combustion gases of said source of heat, a steam and water drum having a steam space therein, a steam outlet for said steam space provided at the top of said drum, return pipes for connecting the upper ends of said water tubes to the steam space of said drum, an upper water outlet near the upper part of said drum, a by-pass pipe connected to said 90 upper water outlet, a lower water outlet at the lower part of said drum, a conduit in communication at one end with the lower end of said water tubes and at the other end with the by-pass pipe and the lower water outlet 95 and controlling means for governing simultaneously the flow from said outlets to said conduit.

3. A water tube steam generator comprising in combination a combustion chamber, 105 a source of heat within said chamber, a set of water tubes subjected to the hot combustion gases of said source of heat, a steam and water drum having a steam space therein, a steam outlet for said steam space provided at the top of said drum, return pipes for connecting the upper ends of said water tubes to the steam space of said drum, an upper water outlet near the upper part of said drum, a by-pass pipe connected to said 110 upper water outlet, a lower water outlet at the lower part of said drum, a conduit in communication with the lower end of said water tubes and means whereby the said conduit may be put into communication either with 115 the by-pass pipe or the lower water outlet.

4. A water tube steam generator according to claim 1, comprising also means for supplying feed water to the lower part of said drum.

5. A water steam generator comprising in combination a combustion chamber, a source of heat within said chamber, a set of water tubes subjected to the hot combustion gases of said source of heat, a steam and water 120 drum having a steam space therein, a steam outlet for said steam space provided at the top of said drum, return pipes for connecting the upper ends of said water tubes to the steam space of said drum, an upper water outlet near the upper part of said drum, a by-pass pipe connected to said upper water outlet, a lower water outlet at the lower part of said drum, a conduit in communication with the lower end of said water tubes and means whereby the said conduit may be put into communication either with the by-pass pipe or the lower water outlet.

6. A water steam generator comprising in combination a combustion chamber, a source of heat within said chamber, a set of water tubes subjected to the hot combustion gases of said source of heat, a steam and water 130 drum having a steam space therein, a steam outlet for said steam space provided at the top of said drum, return pipes for connecting the upper ends of said water tubes to the steam space of said drum, an upper water outlet near the upper part of said drum, a by-pass pipe connected to said upper water outlet, a lower water outlet at the lower part of said drum, a conduit in communication with the lower end of said water tubes and means whereby the said conduit may be put into communication either with the by-pass pipe or the lower water outlet.

drum having a steam space therein, a steam outlet for said steam space provided at the top of said drum, return pipes for connecting the upper ends of said water tubes to the steam space of said drum, an upper water outlet near the upper part of said drum, a by-pass pipe connected to said upper water outlet, a water drum below said steam and water drum and in communication with the lower part of the same a lower water outlet

on said water drum, a conduit in communication with the lower end of said water tubes and means for governing simultaneously the flow from said outlets to said conduit.

6. A water tube steam generator according to claim 5, comprising also means for supplying feed water to said water drum.

In testimony whereof I have signed my name to this specification.

AUGUSTE GOSSE.
